US0D1046561S

(12) **United States Design Patent** (10) Patent No.: **US D1,046,561 S**
(45) Date of Patent: ** Oct. 15, 2024

(54) **BACKPACK COOLER**

(71) Applicant: **YETI Coolers, LLC**, Austin, TX (US)

(72) Inventors: **Jeffrey Charles Munie**, Austin, TX (US); **Kyle Edward Rogers**, Austin, TX (US); **Donald Edward Desroches**, Austin, TX (US); **John Loudenslager**, Austin, TX (US); **Derek G. Sullivan**, Austin, TX (US); **Alex Baires**, Austin, TX (US)

(73) Assignee: **YETI Coolers, LLC**, Austin, TX (US)

(**) Term: **15 Years**

(21) Appl. No.: **29/905,254**

(22) Filed: **Oct. 18, 2023**

Related U.S. Application Data

(63) Continuation of application No. 29/856,531, filed on Oct. 14, 2022, now Pat. No. Des. 1,006,548, which is a continuation of application No. 29/801,966, filed on Aug. 2, 2021, now Pat. No. Des. 970,299, which is a continuation of application No. 29/765,057, filed on Jan. 5, 2021, now Pat. No. Des. 927,262, which is a continuation of application No. 29/759,278, filed on Nov. 20, 2020, now Pat. No. Des. 922,828, which is a continuation of application No. 29/686,649, filed on Apr. 5, 2019, now Pat. No. Des. 902,664, which is a continuation of application No. 29/624,134, filed on Oct. 30, 2017, now Pat. No. Des. 848,219.
